WINDOW OPERATING MECHANISM

Filed July 3, 1922

2 Sheets-Sheet 2

UNITED STATES PATENT OFFICE.

LAURENCE M. FOSS, OF AMESBURY, MASSACHUSETTS.

WINDOW-OPERATING MECHANISM.

Application filed July 3, 1922. Serial No. 572,634.

To all whom it may concern:

Be it known that I, LAURENCE M. Foss, a citizen of the United States, residing at Amesbury, in the county of Essex and State of Massachusetts, have invented new and useful Improvements in Window-Operating Mechanism, of which the following is a specification.

This invention relates to mechanism for operating a sliding window, movable in guides in a frame, such as the hinged frame of the door of a limousine, or other vehicle body, said frame having an opening which may be closed and opened by the sliding window, the window being closed by an upward movement.

The chief object of the invention is to provide mechanism adapted to be manually operated by a minimum expenditure of muscular force in raising the window, and adapted also to maintain the window in any position to which it may be moved, the mechanism being compactly arranged and conveniently installed.

Other objects of the invention will appear hereinafter.

The invention is embodied in the improved mechanism hereinafter described and claimed.

Of the accompanying drawings forming a part of this specification,—

Figure 1 is a side elevation of a door, the window of which is fully opened, the operating mechanism, excepting the crank-shaft and its crank hereinafter described, being concealed by a facing board and the window being opened.

Figure 2 is a similar view on a larger scale, the facing board being removed and a portion of the frame broken away.

Figure 3 is a view similar to Figure 2, showing the window partially closed, one position of the window being shown by full lines, and another by dotted lines.

Figure 4 is an enlargement of a portion of Figures 1, 2 and 3.

Figure 5 shows the inner side of the portion represented by Figure 4.

Figure 6 is a section on line 6—6 of Figures 1 and 4.

Figure 7 is a section on line 7—7 of Figure 3.

Figure 8 is a section on line 8—8 of Figure 3.

Figure 9 is a view similar to Figure 6, showing a modification.

The same reference characters indicate the same parts in all of the figures.

The frame, designated as a whole by the reference numeral 12, may be the hinged frame of the door of a limousine body, and may be of any suitable construction providing upright guides 13, one of which is shown in section by Figure 8, for a sliding window. Said window may also be of any suitable construction, and in this instance includes a glass pane 14, and a marginal metal frame 14^a, the upright members of which are slideable in the guides 13. The frame 12 has the usual opening 12^a in its upper portion, and the window, when fully lowered, as shown by Figures 1 and 2, entirely exposes said opening, and when fully raised, covers the opening.

Fixed to the window, and preferably to the lower end member of the frame 14^a, is an inwardly projecting stud, which is substantially equidistant from the upright or guided edges of the window. Said stud is preferably composed of a fixed axle member or arm 16, attached to a fixed ear 17 (Figure 7), on the window, and a grooved anti-friction roll 18, journaled to rotate freely on said arm.

19 represents a traveller, here shown as an oblong metal plate, having a longitudinal slot with opposed parallel pushing edges 20, contacting with opposite sides of the periphery of the roll member 18, of the window stud.

The traveller is connected with the frame by a pair of parallel motion links 22 and 23, pivoted at 24 to a fixed ear or bracket 25 on the frame, and at 26 to one end portion of the traveller, the arrangement being such that said links maintain the slot edges 20 substantially at right angles with the path of movement of the window, and, when swung on their pivots 24, cause a combined endwise and edgewise movement.

of the traveller, so that the slot edges 20 are in sliding and pushing engagement with the window stud.

I provide manually operable means for swinging said links in unison, and thereby causing the traveller to assume different positions, as indicated by Figures 2 and 3, and to slide the window in the frame. I prefer to embody said means in a crank-shaft 28, journaled in fixed bearings on the frame, and provided with a pinion 29, and a rack-bar meshing with the pinion and pivoted to the link 22. As here shown, the rack-bar includes a toothed outer section 30, and an inner section 31, pivoted at 32 to the outer section, the sections being connected by screws 33. The bearings of the crank-shaft are preferably formed in a circular plate 34, which is fixed to a cross-bar 35, attached to the frame 12, and in a strip 340 attached to and offset from the plate 34. Said plate is inserted in a circular socket 36, in the cross-bar, and is provided with a marginal annular wall 37, seated on the wall of said socket, and with an annular flange 38, seated on the outer side of the board. The plate 34 is offset from the outer side of the board, as shown by Figure 6, to form a recess for the operating crank, whereby the shaft is rotated. Said crank is preferably foldable, so that it may be housed in said recess when not in use, as indicated by Figure 4, and in part by dotted lines by Figure 6. The crank includes an inner section 39, fixed to the shaft and located mainly in the recess formed by the plate 34 and wall 37, and an outer section 40, which is forked at one end to bestride the section 39, and is pivoted to the latter by a pin 41. When the crank is extended, as shown by full lines in Figure 6, the section 40 stands outside the cross-bar 35, so that its handle 42 may be grasped by the operator. When the crank is folded, it enters the recessed plate 34, and its handle enters an orifice 43 in said plate, as shown by dotted lines, the crank being thus stored out of the way. Two handle-receiving orifices 43 may be provided as shown by Figure 4, to permit the folding of the crank in different angular positions.

A facing board 45 (Figures 1, 4 and 6) is secured to the frame 12 and to the cross-bar 35, and forms the inner side of the portion of the door below the opening 12^a, as shown by Figure 1, the cross-bar and the entire mechanism above described, excepting the crank-shaft and its crank, being concealed by said facing board which, in a limousine door, may be surfaced with cloth to match the upholstery.

The facing board has a circular opening 46, coinciding with the socket 36 in the cross-bar. A ring 47 is nested in the wall portion 37 of the plate 34, and covers the

margin of the opening 46. Said ring has an annular flange 48 overlapping the facing board 45 around the opening 46. Screws 49 secure the flanges 38 and 48 and the intermediate portion of the facing board 70 to the cross-bar.

The cross-bar 35 is cut away to form a slot 50, extending through its lower edge into the socket 36, and a recess 51 extending from said socket partly to the upper edge 75 of the cross-bar. The rack-bar is movable endwise in said slot, socket, and recess, and is held in engagement with the pinion 29 by a stud or roll 52. When the crank-shaft is rotated, the rack-bar swings the links 22 80 and 23 and the traveller upward or downward, as the case may be. When the traveller is fully lowered, as shown by Figure 2, the window stud is in the outer end portion of the traveller slot, and the window 85 is fully opened. When the traveller is raised, it is at the same time moved endwise in the direction of arrow x, its slot edges sliding in contact with the window stud. When the links reach a substantially horizontal position, the window stud is at the inner end portion of the traveller slot, as shown by Figure 3. When the links are swung further upward, the slot edges slide in the opposite direction indicated by arrow y, Figure 3.

It will be seen that the slotted traveller is adapted to apply window-raising or lowering pressure to a window stud which is midway between the guided edges of the window, so that the window is evenly balanced on the traveller, and the pressure of its guided edges on the upright guides 13 is practically equalized, hence the window has no tendency to bind on the guides, and is 100 adapted to be raised by a minimum expenditure of muscular force.

The pinion and rack connection between the operating shaft and the links, is adapted to maintain the window, through the links, 110 the traveller, and the stud, in any position to which it may be raised or lowered.

To further minimize the force required to raise the window, I provide counterbalancing means embodied in a spring 54, secured at 55 to the frame 12, and an arm 56, pivoted at 57, to an ear on the frame. The spring is connected at 58 with the arm, and presses the free end portion of the latter upward against a trundle-roll, or other projection, 120 59, on the link 22.

Although each of the links 22 and 23 may be straight and parallel with the other, I prefer to give the link 22 a somewhat angular form, the lower edge thereof having 125 a salient formation. The link thus formed cooperates to better advantage with the spring-pressed arm 56 than would be the case if the link were straight.

Figure 9 shows a modification in which 130

I substitute for the plate 34, located within the socket 36, a plate 34^a, attached to the outer side of the cross-bar and covering one end of the socket. The crank section 39 is, in this case, entirely outside the cross-bar, but in view of the fact that the plate has the orifices 43, either of which is adapted to receive the handle 42 of the section 40, the crank when folded, does not project objectionably into the interior of the vehicle, the handle being stored in the socket 36 as before. The facing board is clamped around its opening by a ring 48^a, substituted for the flange 48.

15 I claim:

1. Window-operating mechanism comprising, in combination, a frame; a window slideable in guides in the frame; a stud fixed to the window substantially equidistant from the guided edges thereof; a traveller having opposed parallel pushing edges contacting with said stud; and traveller-operating means movably connecting the traveller with the frame, maintaining said edges substantially at right angles with the path of movement of the window, and organized to cause a combined endwise and edgewise movement of the traveller, and thereby slide the window in the frame, the said traveller edges being in sliding and pushing contact with the window stud.

2. Window-operating mechanism comprising, in combination, a frame; a window slideable in guides in the frame; a stud fixed to the window substantially equidistant from the guided edges thereof; a traveller having opposed parallel pushing edges contacting with said stud; swinging links pivoted to the frame and to the traveller, and arranged to maintain said edges substantially at right angles with the path of movement of the window, and to cause a combined endwise and edgewise movement of the traveller; and manually operable means for swinging said links, and thereby sliding the window in the frame, the said traveller edges being in sliding and pushing contact with the window stud.

3. Window-operating mechanism substantially as specified by claim 1, the said stud being provided with a grooved anti-friction roll contacting with the edges of the said slot.

4. Window-operating mechanism comprising, in combination, a frame; a window slideable in guides in the frame; a stud fixed to the window substantially equidistant from the guided edges thereof, a traveller having opposed parallel pushing edges contacting with said stud; swinging links pivoted to the frame and to the traveller; and arranged to maintain said edges substantially at right angles with the path of movement of the window, and to cause a combined endwise and edgewise movement of the traveller; a

manually rotatable crank-shaft journaled in a fixed bearing on the frame, and provided with a pinion; and a rack-bar meshing with said pinion and pivotally connected with one of said links to swing the links and the 70 traveller when the shaft is rotated.

5. Window-operating mechanism comprising, in combination, a frame; a window slideable in guides in the frame; a stud fixed to the window substantially equidistant from the guided edges thereof; a traveller having opposed parallel pushing edges contacting with said stud; swinging links pivoted to the frame and to the traveller, and arranged to maintain said edges substantially at right 80 angles with the path of movement of the window, and to cause a combined endwise and edgewise movement of the traveller; a fixed cross-bar on the frame beside the path of the window and provided with a socket; a fixed plate extending across said socket and provided with a handle-receiving aperture; a shaft journaled in bearings on the plate and provided with a pinion, located in said socket, and with a sectional crank composed of an inner section fixed to the shaft, and an outer section hinged to the inner section, and provided with a handle, the crank being foldable, and the arrangement such that when the crank is folded, the handle enters the plate orifice and is stored in said socket; and a rack-bar meshing with said pinion, and pivotally connected with one of said links to swing the links and the traveller 85 when the shaft is rotated.

6. Window-operating mechanism substantially as specified by claim 5, the said plate being provided with an annular wall portion seated on the margin of the cross-bar socket, 105 an annular flange seated on the outer side of the cross-bar, and a ring nested in the said wall portion, and provided with an annular clamping flange, adapted to be seated on the outer side of a facing board covering the outer side of the cross-bar, said flanges and facing board receiving fastening members which secure the flanges and a portion of the facing board to the cross-bar.

7. Window-operating mechanism, substantially as specified by claim 2, comprising also window-counterbalancing means including an arm pivoted at one end to the frame, and a spring engaged with the frame and with said arm, and pressing the latter yielding against a projection on one of said links.

8. A door comprising, in combination, a frame having a window opening and upright window guides; a cross-bar below the opening having a socket; a plate extending across said socket, and provided with a handle-receiving aperture; and a crank-shaft journaled in said plate and having a foldable crank adapted to enter said aperture 115 and be stored in said socket, said crank-shaft 120

constituting an element of mechanism for sliding a window in said guides.

9. A door substantially as specified by claim 8, the frame being provided with a facing board below the said opening, and the said plate being provided with an annular wall portion seated on the socket wall, an annular flange seated on the outer side of

the cross-bar, and a ring nested in said wall portion and provided with an annular 10 clamping flange, adapted to bear on the facing board.

In testimony whereof I have affixed my signature.

LAURENCE M. FOSS.
